Des. 213,449
Patented Mar. 4, 1969

213,449

RELIGIOUS CROSS

Carl J. Schuette, 1816 Chestnut Road,
Cleveland, Ohio 44131

Filed Jan. 9, 1968, Ser. No. 10,100

Term of patent 14 years

U.S. Cl. D29—23
Int. Cl. D11—03

FIG. 1

FIG. 2

The essential features of my design reside in the full line disclosure.

I claim:

The ornamental design for a religious cross, as shown and described.
